PRINTING MACHINES

Arthur E. J. Owen, Gates Mills, Ohio, assignor to Addressograph-Multigraph Corporation, Cleveland, Ohio, a corporation of Ohio

Filed June 9, 1960, Ser. No. 35,046

5 Claims. (Cl. 101—142)

This invention relates to printing machines and especially to machines wherein an image is transferred from a master to a blanket and thereafter to a sheet fed between the blanket and a cooperating platen or impression cylinder, the machine therefore being of the kind that operates on the offset principle.

In printing machines of the kind operating on the offset principle, a replaceable blanket is mounted on the blanket cylinder so that the surface of the blanket receives an inked image from a master and such image is then printed on a sheet passed between the blanket and the platen cylinder. Such blankets heretofore have been composed of rubber or have been of such nature that a rubber surface was afforded to receive the image from the master. Machines of this kind are so arranged that a master bearing a particular image may be readily substituted for one bearing another image. Inasmuch as what may well be called a residual image from one master usually remains on the surface of the blanket when a new master is substituted for one previously mounted in the machine, and since in most instances it would be objectionable to have an imprint effected from such a residual image, it is common to thoroughly clean the surface of the blanket as an incident to a change of masters in the machine. Heretofore, this has been effected either manually by resort to a swab or special equipment such as that disclosed in United States Reissue Patent Re. 24,739. Moreover, heretofore when cleaning of the blanket has been effected as aforesaid, a suitable cleaning solution has been resorted to to facilitate removal of any residual or previous image on the surface of the blanket. Such blanket cleaning operations are time consuming and this has been particularly objectionable in those instances where relatively few transfers from the master to the blanket and thence to the sheets receiving the impressions are being effected as in the instance where, for example, a dozen or less impression operations are effected.

It is therefore the primary object of the present invention to supplant a conventional blanket affording a rubber surface as heretofore used in a printing machine of the aforesaid character with a blanket having an image receiving surface from which any previous or residual image may be expeditiously removed as, for example, by removing an image remaining on the surface of the blanket in but a single movement of the blanket past a blanket cleaning means.

Another object of the invention is to resort to a blanket surface capable of retaining an image picked up from a master for the purpose of transferring the same to a sheet to receive the same but from which surface any image remaining thereon is readily removable due to inherent characteristics of the material affording the surface.

Still another object of this invention is to provide a mechanism which may be expeditiously engaged with a blanket surface of the aforesaid character to remove any residual image therefrom and an ancillary object is to include in the mechanism an arrangement whereby a fresh or clean surface may be presented to the blanket surface as required to insure effective removal of any residual image from the blanket surface.

2

A more specific object of this invention is to resort to a blanket having its image receiving face composed of Teflon resin material, that is, a polytetrafluoroethylene material.

Other and further objects of the present invention will be apparent from the following description and claims and are illustrated in the accompanying drawing which, by way of illustration, shows a preferred embodiment of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

15 In the drawings:

FIG. 1 is a vertical sectional view of a typical machine operating on the offset principle and wherein a blanket of the present invention is incorporated;

20 FIG. 2 is a plan view of blanket embodying the present invention;

FIG. 3 is a view taken substantially on the line 3—3 on FIG. 1; and

25 FIG. 4 is a perspective view of a portion of the apparatus illustrated in FIGS. 1 and 3.

While my invention may be utilized in any machine operating on the offset principle as aforesaid, a typical machine in which my invention may be utilized is disclosed in U.S. Patent No. 2,165,231 and which is in the general nature of the machine shown in the accompanying drawing. Thus, the machine as illustrated in the accompanying drawing includes a cylinder 11 on the periphery of which a planographic master or plate P bearing an image to be reproduced may be mounted. The machine also includes a cylinder 12 on the periphery of which a blanket B embodying the present invention may be mounted. The plate P of the blanket B may be removably secured to the peripheries of the cylinders on which they are mounted in any suitable manner as, for example, that disclosed in aforesaid Patent No. 2,165,231. The respective thickness of the plate and blanket are so related one to the other, and to the diameters of the cylinders on which plate and blanket are respectively mounted, that the surfaces of the plate and blanket are in contact one with the other when the cylinders are set in rotation in the direction of the arrows shown on the respective cylinders in FIG. 1. The blanket B on the periphery of the cylinder 12 is adapted to cooperate with a platen or impression cylinder 13, the arrangement being such that sheets disposed on the table 14 may be advanced one at a time into the bight between the cylinder 13 and the blanket B to thereby have an impression carried by the surface of the blanket B transferred to such a sheet. After the sheet has passed between the bight between the blanket B and the platen 13, the sheets are collected in a suitable hopper such as 15.

These cylinders 11 and 12 are respectively mounted on parallel shafts 16 and 17, the opposite ends of which are journaled in suitable bearings afforded in the frame 60 F of the machine as disclosed, for example, in aforesaid Patent No. 2,165,321. A gear as 18 is associated with each cylinder 11 and 12 and such gears are meshed one with the other. Moreover, a gear as 19 meshes with the gear 18 associated with cylinder 11 and also with a gear as 20 that in turn meshes with a gear 21, each of such gears being mounted on shafts journaled in bearings afforded in the frame of the machine. The gear 21 is mounted on a shaft 22 on which there is mounted a pulley 23 about which a belt 24 is passed,

said belt also passing about a pulley 25 on the shaft of the motor M that is suitably mounted in the frame F of the machine. Thus, when the motor M is in operation the cylinders 11 and 12 are driven in synchronism with the surface of the blanket B running in contact with the surface of the printing plate P.

As is customary in the art, an ink receptive or oleophilic image is afforded on the surface of the plate P and ink is applied thereto through the ink train generally indicated by 26 which may be in the nature of that shown in aforesaid Patent No. 2,165,231. The surface of the plate P, other than that whereat an image appears is hydrophilic, and a conventional repellent or moistening solution is applied to this portion of the plate through the moistening unit generally indicated by 27 which may also be in the nature of that disclosed in the just referred to patent. Thus, when the cylinders 11 and 12 are set in rotation, ink is supplied to the oleophilic image on the surface of the plate P and a dampening solution is also applied to the surface of the plate and, as the cylinders 11 and 12 continue in rotation, the ink from the image on the surface of the plate P is transferred to the surface of the blanket B on the cylinder 12. Thereafter, as sheets are passed through the bight between the blanket 12 and the cylinder 13 the ink image on the surface of the blanket B is transferred to such sheets. As is well understood in the art, the image on the surface of the plate P is direct reading so that the image is transferred to the surface of the blanket B in reverse image and therefore in turn the image is transferred in direct reading fashion to the sheet that is fed between the blanket B and the impression cylinder 13.

Heretofore blankets as B employed in printing machines of the aforesaid character have been of rubber or at least of such nature as to afford a rubber surface. Usually all of the ink from the image on the plate and which is transferred to the surface of the blanket B is not completely transferred to sheets passing between the blanket B and the platen or impression cylinder 13 so that what is usually referred to as a residual image remains on the surface of the blanket. Hence, when a plate as P bearing a particular image is removed from the surface of the cylinder 11 and another plate bearing a different image is substituted therefor, it has heretofore been the practice to resort to special solutions to insure that any residual image remaining on the blanket B will be removed therefrom prior to the time ink from the image on a newly installed plate P is transferred to the blanket B. Sometimes this removal of the residual image has been effected manually by resorting to a swab that has been immersed in a cleaning solution and in other instances this has been effected by resorting to special equipment such as that shown in, for example, U.S. Reissue Patent Re. 24,739. When special equipment, such as that just referred to, has been utilized to effect removal of a residual image from the rubber surface of the blanket it has been necessary to effect several revolutions of the cylinder 12 to insure that all the residual image was removed. When the residual image was removed manually by resort to a swab, as aforesaid, the blanket cylinder 12 has usually been advanced manually in a step-by-step manner so as to present succeeding portions thereof in position to have the surface of the blanket thoroughly cleaned. In any event, however, heretofore the removal of a residual image from the rubber surface of a blanket as B has been time consuming, which is oftentimes objectionable.

In accordance with the present invention, at least the image receiving surface of the blanket as B is composed of polytetrafluoroethylene and is readily receptive to conventional inks applied to an image on a plate as P. An image so received on the surface of a blanket of this invention is readily picked up therefrom when a sheet is passed through the bight between the blanket

B and the impression cylinder 13. Even though any image transferred to a blanket having a polytetrafluoroethylene surface is usually completely transferred to a sheet passed between the bight between such a blanket and the impression cylinder 13 there may be instances where a so-called residual image may remain on the surface of the blanket. For reasons stated hereinabove, it is usually necessary to remove any such residual image from the surface of the blanket prior to the time another image is to be transferred thereto from a plate as P. However, I have found that any residual image on the blanket of the present invention may be readily removed therefrom usually by passing the surface of the blanket past means effective to remove any such residual image but a single time.

While the removal of any residual image remaining on the surface of a blanket as B embodying the present invention may be readily effected by passing a dry swab of suitable material over the surface of the blanket usually but a single time, I have found it advantageous to provide suitable means whereby fabric blanket cleaning material may be readily engaged with the surface of the blanket B so that the blanket may be caused to pass thereby to have any residual image on the blanket removed therefrom.

A manually operable form of means suitable for this purpose is illustrated in the accompanying drawing and referring thereto a frame as 28, that is substantially U-shaped in elevation, is provided and the free ends of the arms of such frame are pivotally mounted in the frame F of the machine as indicated at 29 and 30. In profile the frame 28 includes inwardly extending arms as 31 which merge into upwardly extending arms as 32 which in turn merge into outwardly extending arms as 33.

An upwardly extending lug as 34 is provided on each of the arms 31 and a shaft as 35 has opposite ends thereof removably journaled in such lugs. A downwardly extending lug as 36 is provided on each of the arms 33 and a shaft as 37 has opposite ends thereof removably journaled in such lugs. One end of a fabric web as 38 is attached to the shaft 37 and such web is wound on the shaft so that the web may be withdrawn therefrom. A plate 39 extends between, and is attached to, the arms 32 of the frame 28 and is so disposed that the medial portion of the vertical extent thereof is disposed slightly above the horizontal axial plane of the shaft 17 of the cylinder 12 when the frame 28 is in operative position as shown in full lines in FIG. 1. A pad 40 of resilient material, such as sponge rubber or the like, is mounted on the inwardly disposed face of the plate 39. As the web 38 is withdrawn from the supply thereof wound on the shaft 37 the web is passed over the exposed face of the pad 40 and thence to the shaft 35 to which the free end of the web is connected in any suitable way. A knob or handle as 41 is associated with one end of the shaft 35 and by rotating the same the web 38 may be caused to wind up on the shaft 35. In this way a clean portion of the web 38 may be disposed over the surface of the pad 40 whenever the need so to do arises. Spring washers as SW are respectively disposed between the inner faces of the lugs as 34 and adjacent shoulders on the shaft 35. Similar spring washers SW are respectively disposed between the inner faces of the lugs 36 and adjacent shoulders on the shaft 37. The spring washers SW impress a friction drag on the shafts 35 and 37 whereby the web 38 may be maintained in a taut condition. It will be understood that any suitable means may be resorted to provide such a friction drag in order that the web will be maintained taut.

A handle as 42 is provided on the body of the U-shaped frame 28 and may be grasped so as to thereby rock the frame 28 about the pivotal supports 29 and 30 into the broken line position thereof shown in FIG. 1. So to do brings the portion of the web 38 overlying the pad 40 into engagement with the adjacent surface of the blanket B as shown in broken lines in FIG. 1. When such a portion of

the web 38 is engaged with the blanket B the cylinder 12 is rotated to cause the surface of the blanket to move past the portion of the web 38 disposed over the pad 40 and in so doing any residual image on the surface of the blanket B is picked up by the web 38 usually in but a single movement of the surface of the blanket past the web.

As best shown in FIG. 4, a spring 43 is disposed about the boss of the pivotal mounting 30 of one of the arms 31. The end 44 of such spring is fixed to the boss and the opposite end 45 of the spring is engaged with the arm 31 so that the spring will be effective to bias the frame 28 in a counterclockwise direction as viewed in FIG. 1. A similar spring bias is also associated with the other arm 31 of the frame 28. Rods as 46 are mounted in the frame F and are disposed in position to be engaged by the outwardly disposed faces of the lugs as 36 to thereby limit the biasing effect of the spring 43 so as to thereby normally dispose the frame 28 in the full line position thereof shown in FIG. 1 with the portion of the web 38 disposed over the pad 40 out of engagement with surface of the blanket B.

As has been stated, at least the surface of the blanket B is composed of a polytetrafluoroethylene material. Such a surface may be afforded either by resort to polytetrafluoroethylene film of appropriate thickness, but more advantageously such material is applied as a coating or is impregnated into suitable porous structures of which canvas duck or other fabric are illustrative. It is essential, however, that the surface of the polytetrafluoroethylene that is to receive the image be smooth, and to this end the surface may be calendered to insure the desired smoothness. If resort is had to an aqueous dispersion of polytetrafluoroethylene, such dispersion is heated to a sufficient degree to remove the water. In order that a strong continuous film will be afforded, such polytetrafluoroethylene material may be sintered at 680—700° F. after drying. In some instances it may be advantageous to resort to a relatively thin film of polytetrafluoroethylene material and to mechanically connect the film to a suitable support of appropriate thickness as by riveting or the like. The essential aspect of this invention is that a strong, smooth film of polytetrafluoroethylene material afford the surface of the blanket that is to receive the image, since so to do insures proper transfer of ink from the image, and therefore, the image to the sheet that is to receive the same, and this also insures that any residual image or the like remaining on the surface may be expeditiously removed therefrom, as explained hereinabove.

The blanket B, as shown in FIG. 2, is rectangular in outline. At least one of the shorter ends (and desirably both shorter ends) of the blanket is scalloped and has slots formed in the segments between recesses afforded in the scalloped edge. This enables the ends of the blanket to be readily attached in the means afforded in offset printing machines to secure the blanket on the periphery of the blanket cylinder of such a machine. However, other suitable attaching elements may be afforded at one or both of the shorter ends of the blanket without departing from the purview of this invention.

In operation a plate as P will be mounted on the cylinder 11 in the usual manner. Thereafter, ink is applied to the image on the plate through an ink train as 26 and a moistening or repellent solution is applied to the plate through a moistening attachment as 27. The ink is of such nature that it will be picked up by the oleophilic image on the surface of the plate P. Then, as succeeding portions of the surface of the plate P come into contact with succeeding portions of the blanket B, ink from the image will be transferred to the surface of the blanket B. Thereafter, as successive portions of the blanket B move into contact with a sheet disposed between the platen or impression cylinder 13, ink on the surface of the blanket will be transferred to the sheet to thereby afford an impression on the sheet of the inked image on the plate P. When the desired number of sheets to be so imprinted have been advanced from a table as 14 through the eight

between the blanket and the impression cylinder operation of the machine is interrupted. The plate as P which has been mounted on the cylinder 11 is then removed so that a new plate may be substituted therefor. Prior to the time a new plate as P is mounted on the cylinder 11, the cylinder 12 will be set in rotation and by grasping the handle 42 the portion of the web 38 disposed over the pad 40 will be brought into engagement with the surface of the blanket B. As succeeding portions of the blanket B come into contact with the aforesaid portion of the web overlying the plate 40 any residual image or the like thereon is picked up by the web 38. Usually no more than a single revolution of the cylinder as 12 will be required to remove any residual image from the surface of the blanket B when such surface is a polytetrafluoroethylene material in accordance with this invention.

As the portion of the web 38 disposed over the pad 40 becomes soiled by reason of picking up residual images and the like from the surface of the blanket B, the web may be advanced by operating the handle 41 to thereby withdraw the web from the shaft 37 and to wind the same on the shaft 35 and such an operation will be effected whenever in the judgment of the operator of the machine it is necessary so to do.

While I have illustrated and described the present invention from the standpoint of one embodiment, it will be appreciated that this is capable of variation and modification, and I therefore do not wish to be limited to the precise details set forth, but desire to avail myself of such changes and alterations as fall within the purview of the following claims.

I claim:

1. In an offset printing machine wherein an image carried by a master mounted on a plate cylinder is transferred to a blanket on a blanket cylinder and from thence to a sheet fed between the blanket and a cooperating impression cylinder, a blanket secured to said blanket cylinder having the image-receiving surface thereof composed of polytetrafluoroethylene.
2. A blanket adapted to be removably mounted on the blanket cylinder of an offset printing machine, said blanket being of generally rectangular outline and having attaching elements integrally associated with at least one end thereof, said blanket having at least one surface composed of polytetrafluoroethylene.
3. In an offset printing machine wherein an image carried by a master mounted on a plate cylinder is transferred to a blanket on a blanket cylinder and from thence to a sheet fed between the blanket and a cooperating impression cylinder, a blanket secured to said blanket cylinder having the image-receiving surface thereof composed of polytetrafluoroethylene, and means engageable with the image-receiving surface of the blanket when the blanket is mounted on the blanket cylinder for removing any residual image or the like from such surface in a revolution of the blanket cylinder during which the means is engaged with said surface.
4. In an offset printing machine wherein an image carried by a master mounted on a plate cylinder is transferred to a blanket on a blanket cylinder and from thence to a sheet fed between the blanket and a cooperating impression cylinder, a blanket secured to said blanket cylinder having the image-receiving surface thereof composed of polytetrafluoroethylene, and means affording a fabric surface engageable with the image-receiving surface of the blanket when the blanket is mounted on the blanket cylinder for removing any residual image or the like from said blanket surface in a revolution of the blanket cylinder during which the fabric surface is engaged with said blanket surface.
5. In an offset printing machine wherein an image carried by a master mounted on a plate cylinder is transferred to a blanket on a blanket cylinder and from thence to a sheet fed between the blanket and a cooperating impression cylinder, a blanket secured to said blanket cylinder,

der having the image-receiving surface thereof composed of polytetrafluoroethylene, means including a web of fabric affording a fabric surface engageable with the image-receiving surface of the blanket when the blanket is mounted on the blanket cylinder for removing any residual image or the like from said blanket surface in a revolution of the blanket cylinder during which the fabric surface is engaged with said blanket surface, and means for advancing said web so that succeeding portions of the web will afford the aforesaid fabric surface.
